UNITED STATES PATENT OFFICE.

WEBB JAY, OF CHICAGO, ILLINOIS.

COMBINED CARBURETER AND VACUUM-FEED DEVICE.

1,311,167.

Specification of Letters Patent. Patented July 29, 1919.

Application filed April 29, 1918. Serial No. 231,315.

To all whom it may concern:

Be it known that I, WEBB JAY, a citizen of the United States, residing at Chicago, in the county of Cook and the State of Illinois, have invented certain new and useful Improvements in Combined Carbureter and Vacuum-Feed Devices, of which the following is a specification, reference being had to the accompanying drawings, forming a part thereof.

The purpose of this invention is to provide an improved device of the nature of a combined carbureter and vacuum fuel feed device, having the functions of the carbureter and the vacuum fuel feed device in a single compact structure. It consists in the features of construction shown and described, as indicated in the claims.

In the drawings:

20 Figure 1 is a vertical section at the line, 1—1, on Fig. 2, of a structure embodying this invention in one of its forms.

25 Fig. 2 is a section at the line, 2—2, on Fig. 1.

Fig. 3 is a partly sectional side elevation of a modified form of the invention showing the upper portion of the vacuum fuel feed tank, section being made axially with respect to the venturi of the carbureter.

30 Fig. 4 is a section at the line, 4—4, on Fig. 3.

In the structure shown in Figs. 1 and 2, a customary form of vacuum fuel feed tank is shown, comprising the vacuum chamber, 1, depending within the reserve chamber or reservoir, 2, both these parts being broken away intermediate their ends for condensing the view, the vacuum chamber containing the usual devices for alternating the dominance of suction and atmospheric pressure, consisting of the suction-controlling valve, 4, air inlet valve, 5, operating float, 6, and lever connections from the float to the valves. The cap plate, 8, of the vacuum fuel feed device to which the chambers, 1 and 2, are attached in the customary manner has mounted upon it, and preferably formed integral with it, as shown, the Venturi tube, 10, of the carbureter, positioned with its axis substantially horizontal and adapted by means of a flange, 10^a, to be secured to the intake manifold of the engine to be served, as seen in Fig. 2, this securing serving to support the entire device comprising the combined carbureter and vacuum fuel feed device. The liquid

fuel supply connection from the main low tank, (not shown), is made by a vertical bore, 13^a, through an up-standing boss, 13, which is conveniently positioned adjacent to and merging in the wall of the Venturi tube as seen in Fig. 2. The atmosphere inlet is afforded by means of a vertical bore, 14^a, in a vertical up-standing boss, 14, similarly positioned at the opposite side of the Venturi tube; and in the same boss a vertical bore, 14^b, leads from the suction port, 14^c, and connection for suction is made into this bore, 14^b, from the Venturi tube, opening into the latter at a point beyond the throat or constricted portion thereof, that is between said constricted point and the intake manifold, as seen at 14^d. The usual connection for admitting atmospheric pressure to the reservoir or reserve chamber, 2, is made by an aperture, 16, leading from the annular interspace between the vacuum chamber and said reserve chamber at the upper end thereof, intersecting a transverse bore, 16^a, which leads into the bore, 16, and is closed at its outer end by a plug, 16^b. The customary goose-neck, 17, is connected to the upper end of the bore, 14^a, for the usual purpose.

The carbureter shown in this construction is of the form which in itself is not a part of the present invention. A valve, 20, is pivoted for swinging in the Venturi tube, at a position a little beyond the throat or most constricted point thereof, fuel supply being admitted through the spindle, 21, upon which the valve is pivoted, said spindle being axially apertured and extending to a central aperture, 20^a, in the valve, which aperture at the closed position of the valve faces inward so as to be exposed to the suction of the engine. The valve has a radial duct, 20^b, extending at right angles to the spindle, 21, and leading to a notch, 20^c, at the periphery of the valve for admitting air for admixture with the liquid fuel as the latter is sucked in through the central aperture, 20^a, of the valve. A boss, 23, upon the upper side of the cap plate, 10, extending transversely to the boss in which the Venturi tube is formed, and intersecting the latter boss substantially at the apex or constricted point of the Venturi tube, is bored from one end as seen at 24^a, to receive the operating stem, 24, of the valve, 20, said stem having at its outer end an operating lever arm, 25, by which the valve

is adjusted by any convenient means not shown. From the other end of the boss it is axially bored at 22 to admit the spindle, 21, above mentioned, which has its enlarged 5 head exteriorly threaded for screwing it into the boss, and a tapered shoulder inward from said head, seating upon the tapered inner end of the bore to insure a liquid-tight fit of the spindle, and thereby confine the 10 admission of the liquid fuel to the axial bore of said spindle seen at 21^b. The outer end of the bore, 22, is closed by screw plug, 26. The fuel supply duct by which the liquid fuel is conducted from the reservoir 15 or reserve chamber 2, of the vacuum fuel feed tank to the carbureter is connected with the bore, 22, by means of a vertical bore, 27, extending from the under side of the cap up into the boss, 23, and opening 20 into the bore, 22, thereof, as seen in Figs. 1 and 2, and the pipe, 28, leading from the lower part of the reservoir or reserve chamber, 2, extends through the annular inter-space between the vacuum chamber 1, and 25 the reserve chamber 2, to reach and be inserted into and made tight at this bore, 27.

For the purpose of trapping a limited quantity of liquid fuel in the pipe, 28, and holding such quantity at a position quite 30 near to the point of discharge in the carbureter throat, the pipe, 28, is formed with a drooped portion or loop situated at the upper part of the annular space mentioned; and to give loop or droop considerable 35 capacity, the pipe, 28, is coiled around the vacuum chamber 1, in said annular inter-space, and the loop or drooped portion is made to comprise the entire coil seen at 28^c. In order that the fuel may be trapped in 40 and not siphoned out of this droop, a small aperture, 28^e, is made at the highest point of what would constitute a siphon, not sufficient to prevent the liquid fuel from being 45 lifted through the tube by the suction discharge point in the Venturi tube, but sufficient, nevertheless to break the siphon, of which said loop would be the shorter limb and the final depending portion of the pipe would be the longer limb if its siphoning 50 character were not prevented by the admission of the atmosphere leak through this port, 28^c.

In the forms shown in Figs. 3 and 4, the carbureter Venturi tube is formed integrally 55 with the cap plate of the vacuum tank, but instead of the Venturi tube being horizontal and upon the top of the cap, it is vertical and appended laterally to the cap. In this position the Venturi tube is braced rigidly 60 with respect to the cap by a rib, 10^b, which is formed with the suction-connected duct, 14^x, leading into the Venturi tube beyond the apex thereof; and in a parallel boss or rib, 10^c, there is formed a duct, 27^x, corresponding to the duct, 27, of the form shown 65

in Figs. 1 and 2, leading into the port, 22^x, (corresponding to the bore, 22, of the other figures,) which is formed in the transversely-extending boss or rib, 23^x, which corresponds to the boss, 23, of the other figures, 70 and has at the opposite side of the Venturi tube the bore, 24^x, forming the seat for the valve-operating stem having the operating lever arm, 25, as in the other figures. 75

I claim:

1. In a combined carbureter and vacuum fuel feed device, the latter comprising a vacuum chamber and a fuel reserve chamber into which the vacuum chamber discharges upon relief of the vacuum in the latter, and 80 means for alternately producing and relieving the partial vacuum in the vacuum chamber, the fuel reserve chamber having means for admitting pressure of the atmosphere upon the surface of the liquid therein, said reserve chamber being as to its entire liquid-containing cavity, situated at a lower level than the mixing chamber of the carbureter, and a duct leading from the lower part of said reserve chamber, terminating in the 85 mixing chamber for discharge of the liquid fuel in the latter by the suction of the engine. 90

2. In the construction defined in claim 1 foregoing, a top or cap member which is 95 common to the vacuum chamber and the liquid fuel reserve chamber, the carbureter mixing chamber being formed integrally with said top cap member. 100

3. In the construction defined in claim 1 foregoing, a top member which is common to the vacuum chamber and the liquid fuel reserve chamber, and which is adapted to carry both said chambers, the carbureter mixing chamber being formed integrally 105 with said top or cap member, and adapted for attachment to the engine intake manifold. 110

4. A combined carbureter and vacuum fuel feed device comprising a mixing chamber and a vacuum fuel feed structure which embodies the vacuum chamber and a liquid fuel reserve chamber into which the vacuum chamber discharges the liquid upon relief of the vacuum in the vacuum chamber; 115 means for producing and relieving the partial vacuum in the vacuum chamber; said fuel reserve chamber having means for admitting the pressure of the atmosphere to the surface of the liquid therein; a top or 120 cap member which is common to the vacuum chamber and to the fuel reserve chamber, the mixing chamber of the carbureter being formed integrally with said top cap member, and a fuel feed duct from the 125 reserve chamber leading from the lower part thereof, upward within said chamber into said top or cap member, and thence in said top or cap member to the mixing chamber. 130

5. A combined carbureter and vacuum

fuel feed device comprising a carburetor mixing chamber, and a vacuum fuel feed device which consists of a vacuum chamber and a reserve liquid fuel chamber into which the
5 vacuum chamber discharges upon relief of partial vacuum in the vacuum chamber, the vacuum chamber and the liquid fuel reserve chamber having a separable cap or top member which is common to the two chambers,
10 the vacuum chamber being positioned within the reserve chamber with an interspace

between their walls; a fuel duct from the reserve chamber to the mixing chamber extending from the lower part of the reserve chamber and thence in said interspace to 1 the top thereof, and thence in said cap member to the mixing chamber.

In testimony whereof, I have hereunto set my hand at Chicago, Illinois, this 10th day of April, 1918.

WEBB JAY.
